UNITED STATES PATENT OFFICE.

FRANK E. BESSLER, OF AKRON, OHIO.

RESILIENT WHEEL.

1,414,542.

Specification of Letters Patent. Patented May 2, 1922.

Application filed September 27, 1919. Serial No. 326,755.

To all whom it may concern:

Be it known that I, FRANK E. BESSLER, a citizen of the United States, residing at Akron, in the county of Summit and State 5 of Ohio, have invented a new and useful Resilient Wheel, of which the following is a specification.

It is the object of this invention to provide a novel means whereby a tire may be 10 connected with a wheel body, so as to afford the necessary resiliency, without resorting to pneumatic elements which are subject to puncture and deterioration.

The invention aims to improve generally 15 and to enhance the utility of devices of the kind hereinafter described.

With the above and other objects in view, which will appear as the description proceeds, the invention resides in the combination 20 and arrangement of parts and in the details of construction hereinafter described and claimed, it being understood that, within the scope of what is claimed, changes in the precise embodiment of the invention 25 shown can be made without departing from the spirit of the invention.

In the accompanying drawings:—

Figure 1 shows in side elevation, a device 30 constructed in accordance with the invention, parts being broken away; and Figure 2 is a cross section on the line 2—2 of Figure 1.

The numeral 1 denotes spokes supporting a wheel body 2 comprising a felly 3 and a 35 felly band 4, the band 4 having a side flange 5, and being provided with a lip 6 engaging one side of the felly 3. Clips 7 abut against the opposite side of the felly 3 and are held to the felly by means of securing elements 40 8. A filler 9 may occupy the space defined by the clips 7, the felly 3 and the felly band 4.

The clips hold a retaining ring 10 coacting with the side flange 5 in a way to be described hereinafter.

U-shaped pivot members 11 are attached by securing devices 12 to the felly band 4. Blocks 14 are provided, the same preferably being resilient and being made of rubber. 50 The outer surfaces of the blocks 14 are curved as shown at 15, whereas the inner surfaces of the blocks are curved as indicated at 16. In the curved surfaces 16, seats or notches 17 are formed, the seats or notches 55 receiving the U-shaped pivot members 11 on the felly band 4, the blocks 14 thus being

assembled with the wheel body 2 for tilting movement circumferentially of the wheel body. The outer curved surfaces 15 of the blocks 14 are supplied with longitudinal 60 ribs 18, which serve to enhance the resiliency of the blocks. The blocks 14 are held between the retaining ring 10 and the flange 5, against movement transversely of the wheel body 2. In the outer portions of the blocks 65 14, elongated transverse slots 19 are formed, these slots extending radially of the wheel. The blocks 14 may be supplied with transverse perforations 20 which serve to enhance the resiliency of the blocks. 70

The numeral 21 denotes a circumferential band, preferably made of metal and of sinuous form, certain of the curved portions 22 of the band resting on the ribs 18 of the blocks 14. The band 21 may possess some 75 resiliency. Others of the curved portions of the band 21 support a circumferential strip 23, the said curved portions of the band and the strip 23 being connected by means of securing members 24. A tire 25 is supported 80 on the strip 23. Side rings 26, constituting retaining means, engage the tire 25 and are united by connecting members 27, the connecting members having a movement, radially of the wheel, in the elongated slots 19 85 of the blocks 14.

In practical operation, when the tire 25 is under pressure, the tire, together with the strip 23 and the sinuous band 21, can move toward the center of the wheel, the connecting members 27 moving in the elongated slots 19 of the blocks 14, and the blocks being compressed. Under circumferential strain, the tire 25 can yield to a slight extent, the blocks 14 rocking on the pivot members 11, 90 because the blocks are engaged in certain of the curved portions 22 of the sinuous band 21. As the blocks 14 yield, the surfaces 16 of the blocks come into contact with the felly band 4 and thus limit the tilting movement 95 of the blocks, on the pivot members 11, circumferentially of the wheel. At first, the blocks 14 yield with some readiness, but when the surfaces 16 of the blocks engage the felly band 4, then the circumferential 100 movement of tire 25 is limited, and further circumferential movement takes place only due to the compression of the blocks 14.

Having thus described the invention, what is claimed is:—

1. In a device of the class described, a wheel body; resilient blocks mounted on the

- body to tilt circumferentially of the body; a sinuous band having curved portions engaged with the blocks; a tire; and means for supporting the tire on the sinuous band.
5. 2. In a device of the class described, a wheel body; resilient blocks mounted to tilt circumferentially of the wheel body and having inclined inner faces spaced from the wheel body but adapted to contact therewith under excessive strains; a sinuous band having curved portions, certain of which cooperate with the blocks; a circumferential strip connected to others of the curved portions of the band; and a tire assembled with the strip.
10. 3. In a device of the class described, a

wheel body; resilient blocks mounted on the body to tilt circumferentially of the body and having inclined inner faces spaced from the body but adapted to contact with the 20 body under an excessive strain, the outer surface of each block being provided with longitudinally disposed ribs, enhancing the resiliency of the blocks; a tire; and means for supporting the tire on the ribs.

25

In testimony that I claim the foregoing as my own, I have hereto affixed my signature in the presence of two witnesses.

FRANK E. BESSLER.
